SECTIONAL BUILDING CONSTRUCTION

Francis Vaux Wilson, Jr., Morrisville, Pa., and John W. Germond, Trenton, N. J., assignors to Homasote Company, Incorporated, Fernwood, N. J., a corporation of New Jersey

Application July 27, 1939, Serial No. 286,840

11 Claims. (Cl. 20—1)

This invention relates to building constructions and particularly to methods and means for use in the construction and assembly of building sections.

While the present invention is particularly applicable to constructions utilizing a modular principle of design numerous features of the invention are of general application and are not limited to constructions of modular design.

The patent to Bemis No. 1,878,367 describes and claims a system of design wherein the horizontal dimensions of walls and partitions of a building are multiples of a unit referred to as a modulus. Although the modulus may be chosen arbitrarily or so as to permit the use of any particular type of structural element it is found in practice that the use of a modulus which is more or less than a whole number of inches in length introduces so many complications, by reason of the addition and multiplication of fractions, that the system becomes very difficult in its operation.

For most practical purposes a four inch modulus is desirable. However conventional wooden timbers such as the "2 by 4's" ordinarily used in wooden or frame buildings are not actually 4 inches wide or 2 inches thick but instead are usually either $3\frac{1}{2}$ " by $1\frac{1}{2}$ " or are $3\frac{3}{4}$ " by $1\frac{1}{4}$ " in cross section. Other conventional timbers are similarly cut or trimmed to fractional inches in width and thickness although referred to in the trade as "2 by 8's," "4 by 6's" or by other similar terms. Because of these facts modular systems of construction have heretofore been limited in their application to structures employing specially fabricated metal framework or specially cut timbers and to systems using a modulus which includes a fractional part of an inch.

In order to overcome these objections to modular systems and permit the use of conventional wooden timbers in a building of modular design and further in order to produce building sections which can be made and assembled readily we have developed a type of construction in which conventional wooden timbers are employed but in which they are so arranged as to lend themselves to a modular system of design. In those portions of the construction wherein the use of the modulus is of importance novel arrangements or sub-assemblies are employed but these sub-assemblies are not formed of specially cut timbers but are made from conventional timbers of the type used in forming the building sections or elsewhere in the building.

Sub-assemblies and building sections embody-

ing our invention may be of various forms but it is found that the sub-assemblies generally fall into three classes as follows:

5 (1) Corner sub-assemblies for use in corner constructions;

(2) Three-way sub-assemblies for use in those locations wherein a partition or wall abuts a wall extending on either side of the partition; and

10 (3) Four-way sub-assemblies for use in those locations wherein partitions or walls extend in four directions from a common point.

In addition to these usual sub-assemblies there sometimes are other special locations and arrangements wherein other sub-assemblies embodying the present invention may be used to advantage.

Building sections embodying our invention ordinarily include one or more of the foregoing sub-assemblies together with conventional timbers employed as studding or for other purposes. In many instances additional sub-assemblies for door and window openings are included in a building section. Typical sub-assemblies for wall openings are described and claimed in our co-pending application Serial No. 299,052 filed October 12, 1939.

The building sections preferably include surfacing material such as wall board or other sheet material and as hereinafter pointed out the strength of the completed section may be very greatly increased by the use and application of wall board in accordance with our invention.

One of the objects of the present invention 35 is to facilitate the use of conventional timbers in a modular design of building construction utilizing a modulus which is a whole number of inches in length.

Another object of our invention is to provide 40 sub-assemblies formed of conventional wooden timbers and designed for use in a modular building construction.

A further object of our invention is to provide 45 a novel method of constructing and assembling elements to produce a building section for use in a modular system of construction.

Another object of our invention is to provide 50 a novel type of building section adapted to be assembled with other sections in the erection of a house.

These and other objects and features of our invention will appear from the following description thereof in which reference is made to the figures of the accompanying drawings.

In the drawings:

Fig. 1 is a diagrammatic horizontal sectional view of a portion of a building constructed on a modular principle of design.

Fig. 2 is a diagrammatic horizontal sectional view of an alternative form of construction embodying our invention.

Fig. 3 is a perspective of a typical building section embodying our invention with parts thereof broken away to illustrate the details of construction more clearly.

In that form of our invention illustrated in Fig. 1 a building is formed of a number of separately fabricated sections adapted to be assembled in the erection of a building. The section 2 cooperates with a section 4 to form a corner; a section 6 cooperates with the section 2 to form an abutting partition; and sections 8 and 10 extend from opposite sides of the section 2 to form intersecting walls which extend in four directions at right angles to each other. The sub-assembly 14 at the corner will hereinafter be referred to as a "corner sub-assembly"; the sub-assembly 16 located at the intersection of the section 6 with the section 2 will be referred to as an "intermediate 3-way sub-assembly," whereas the sub-assembly 18 located in section 2 and between the ends of the sections 8 and 10 will be referred to as an "intermediate 4-way sub-assembly."

In the construction of Fig. 2 the corner construction and sub-assembly 14 is similar to that of Fig. 1 but the sections 20 and 22, which correspond to the single section 2 of Fig. 1, are joined adjacent the abutting section 24. In this location a "terminal 3-way sub-assembly" 26 is used for securing the sections 20, 22 and 24 together. A "terminal 4-way sub-assembly" is shown at 28 for securing the section 22 to sections 30, 32 and 34 to produce intersecting walls which may be similar in location and appearance to the walls adjacent the "intermediate 4-way sub-assembly" 18 of Fig. 1.

Each of the sub-assemblies 14, 16, 18, 26 and 28 is formed of a plurality of conventional wooden timbers and these timbers are so arranged as to present "over-all" dimensions which serve to locate the ends of sections and the joining surfaces of the assemblies on a modular line of the building. For this purpose the exposed surface 38 of central timber 38 of the corner sub-assembly 14, to which the end of section 4 is joined, is displaced with respect to the adjacent surfaces 40 of the outer timbers 42 of the sub-assembly. In like manner, the exposed surface 44 of the central timber 46 of sub-assembly 16, to which the end of section 6 is joined, is displaced with respect to the adjacent surfaces of the outer timbers 48. The exposed surfaces 50 and 52 of the central timbers 54 and 56 of sub-assembly 18, to which the ends of sections 8 and 10 are joined, are displaced from the adjacent surfaces of the outer timbers 58. The sub-assemblies 14, 26 and 28 of Fig. 2 are similarly formed to insure the location of each of the joining surfaces on a modular line of the construction.

The distance which the center timber is displaced with respect to the outer timber is made sufficient to compensate for the difference between a dimension of the outer timber and that of the modulus. This is done to preserve the modular dimensions so that the center lines of the sections may be located a whole number of moduli apart and the joining surfaces of the sub-assemblies, and therefore the ends of abutting sections, may also be located a whole number of moduli apart and one-half of a modular dis-

tance from the center line of the section in which they are embodied.

Since the outer timber of the subassembly is ordinarily centered with respect to the section, the center timber is made to project outward beyond the edge of the outer timber a distance equal to the difference between one-half of the modulus and one-half the width or transverse dimension of the outer timber. In other words 10 the center timber is displaced with respect to the outer timber a distance equal to one-half the difference between a dimension of the outer timber and the dimension of the modulus. In this way the joining surfaces of the sub-assemblies in 15 each section are so located as to insure the proper location of the ends of adjacent or abutting sections and the sections themselves are formed to present surfaces which fit accurately for assembly in erecting a building.

20 As shown in Fig. 3 the central timber of the sub-assembly need not extend throughout the length of the sub-assembly but may be in the form of blocks located adjacent the ends and at the middle of the sub-assembly or at other points 25 as required to insure the necessary strength and positioning of the parts forming the sub-assembly.

Those surfaces of the sub-assemblies to which 30 no sections are attached and the surfaces of the sections between partitions need not lie exactly 35 on a modular line because they are not engaged by other modularly designed elements. It is therefore possible to use conventional timbers as studding 60 and in other constructions such as 33 assemblies for door or window openings located between the ends of a section.

When the studs 60 are made of timber of the same width as the outer timbers used in forming the sub-assemblies, wall board, metal lath or 40 other wall forming material may be applied to the sections very readily. Thus wall boards 62 may be applied to the surface 48 of the outer timber 42 of the sub-assembly 14 and to the corresponding surface 64 of the outer timber 48 of the sub-assembly 16. The portion of the wall board between the sub-assemblies will then bear 45 directly against the edges 66 of the studs 60 and may be secured thereto for support. The opposite edges 68 of the outer timbers 42 and 48 and 50 of the studs 60 are in alignment and present surfaces to which the wall board 70 may be secured to form a completed wall section.

By this arrangement conventional wooden timbers such as standard "2 by 4's," "2 by 8's" etc. 55 can be used in forming sub-assemblies and wall sections which conform to design based upon any desired modulus.

Both modular and non-modular elements are embodied in the sections without introducing 60 complications in the system.

In forming building sections embodying our invention the dimensions of the section and the number, type and location of the sub-assemblies required are determined from the building plan. 65 The sub-assemblies are first made by nailing or otherwise securing the center and outer timbers together in the proper displaced relation and are then placed on a suitable support such as the jig table described and claimed in the copending application of Wilson and Newbeck Serial No. 209,794 filed May 9, 1938 or of our co-pending application Serial No. 314,216 filed January 17, 1940. They are positioned so that the ends thereof engage a top plate 72 and a bottom plate 74 as shown in Fig. 3. If sub-assemblies for door 75

or window openings such as the window sub-assembly 16 are used these are also located with the upper and lower ends thereof in engagement with the top and bottom plates. The studs 68 are then placed on 16" centers starting from one sub-assembly and working toward another after which the parts are secured together by nailing or otherwise.

The section is completed by the application of wall forming material such as the wall boards 62 and 70 of Fig. 3 to the frame work of timber. The wall boards are cut or applied as shown so that they engage opposite sides of the studs and have the edges thereof resting upon those surfaces of the sub-assemblies adjacent the joining surfaces of the central timbers of the sub-assemblies. The joining surfaces of the sub-assemblies are thus exposed to insure proper location and fitting of the sections in erecting the building.

It will be noted that in forming the corner at the left hand end of Fig. 1 the section 2 overlaps the end of section 4 and the wall board 80 on the outer face of section 4 projects beyond the end stud 82 of section 4 to cover the outer face 84 of the outer timber 42 of sub-assembly 14. Wall board 80 thus cooperates with wall board 70 of section 2 to present a neat corner to which a corner molding strip may be applied.

It is important that the center line 86 of section 4 be spaced a distance equal to a whole number of moduli from the center line of other sections or parts of the structure. Since the projecting end of wall board 80 on section 4 overlies the end of section 2 the outer edge 88 of end stud 82 is in line with the surface 84 at the end of section 2 and the center line of section 4 is located a distance inward from the end of section 2 equal to one-half the width of the end stud 82. If this stud is a conventional timber such as "2 by 4" which is actually only 3 $\frac{1}{8}$ " in width the center line will be located 1 $\frac{1}{8}$ " in from the end of the section 2.

Under these circumstances if the section 2 were of full modular dimensions and the center line 86 of section 4 located only 1 $\frac{1}{8}$ " in from the end of section 2 it is apparent that the center line would be spaced $\frac{1}{8}$ " from its modular position and section 4 would not be so positioned as to cooperate with other sections. This is overcome in practice and the center line of section 4 properly located by forming all overlapping sections, such as section 2, a whole number of moduli in length—less $\frac{1}{8}$ inch. Abutting sections can then be made with full modular dimensions and will be properly spaced with their center lines full modular distances apart.

Certain other deviations from strictly modular lengths and measurements are sometimes necessary or desirable to facilitate the construction and assembly of sections in erecting a building. Such deviations are described fully in a book entitled "Tomorrow's Homes" by F. Vaux Wilson, Jr., but in order to simplify the description of our invention in the present application they have been ignored. Therefore it should be understood that reference to "modular" dimensions in the description and claims of this application is intended to include both dimensions which are strictly modular and dimension having related deviations to conform to a modular system such as the deviations referred to above.

In the preferred form of our invention the wall board or wall forming material employed is in the form of a single continuous sheet of material such as "Homasote" and any door or window

openings are cut out so that the sheet extends from one end of the section to the other. The sheet is then secured to the top and bottom plates and to the studs. The edges of the sheet may be secured to the outer timbers of the end sub-assemblies or members of the section but when a corner construction of the type shown and described in the application of Cormie Serial No. 284,425 filed July 14, 1939 is used the edge of the sheet overlying the outer timber of a corner sub-assembly is not secured directly thereto.

The use of a single sheet of wall forming material as described is found to give the section remarkable strength and rigidity. Comparative tests on sections formed with a single sheet of "Homasote" applied thereto as the wall forming material have shown that the strength of a section, that is the resistance to displacement on applying force to one corner while holding the diagonally opposite corner stationary, is 272% greater than the strength of a similar section having $\frac{3}{4}$ " by 8" sheathing applied thereto parallel to the longitudinal edge of the section, and is 30% stronger than a section in which such sheathing is applied diagonally of the section. Moreover, the displacement of the corner of a section embodying the present invention, upon failure was only 1.3" whereas the displacement of the diagonally sheathed section on failure was 3.1" and that of the parallel sheathed section was 8.5".

The surprising strength of sections embodying the present invention is believed to be due not only to the use of a single sheet of wall forming material on the framework but also is due in part at least to the use of sub-assemblies which are built right into the section and provide the section itself with the strength of the corner posts or columns to which the sections of prior prefabricated buildings have been secured and by the elimination of special tongue and groove or other interfitting parts for joining the sections.

The sections of the present invention are secured together by toe nailing, direct nailing or by the use of any desired form of bolts, cleats, screws or the like.

The size and form of any particular section and the type and construction of any particular sub-assembly used in forming a section embodying our invention will be determined from the building plan and while each wall of a room or enclosure will ordinarily be formed of only one section, two or more sections may be used particularly when the room is very long and the size of the section would be too great for easy handling or erection.

The method of assembling the parts to form the sub-assemblies and sections also may be varied considerably to facilitate the application thereof. It should therefore be understood that the forms of our invention shown in the drawings and described above and the methods of fabrication of sections and sub-assemblies are intended to be illustrative of our invention and are not intended to limit the scope thereof.

We claim:

1. A building section adapted to be assembled with other sections to form the vertical walls of a structure, said section having a vertically and longitudinally disposed central plane, and having horizontal dimensions which are a whole multiple of a modulus that is a whole number of inches in length, said section embodying a sub-assembly located in said section in position to be

engaged by the end of another section and comprising two conventional wooden timbers having their longest dimensions extending vertically in the section and having horizontal dimensions which are not a whole number of inches in length, said timbers being secured together with one timber centered with respect to the central plane of said section and the other timber displaced horizontally with respect to said first timber and presenting a vertically disposed surface lying in a modularly disposed plane of the structure to position the end of another section on a modular line in the structure.

2. A building section adapted to be assembled with other sections to form the vertical walls of a structure, said section having a vertically and longitudinally disposed central plane, and having horizontal dimensions which are a whole multiple of a modulus that is a whole number of inches in length, said section embodying a sub-assembly located in said section in position to be engaged by the end of another section and comprising two conventional wooden timbers having their longest dimensions extending vertically in the section and having horizontal dimensions which are not a whole number of inches in length, said timbers being secured together with one timber centered with respect to the central plane of said section and the other timber displaced horizontally with respect to said first timber and presenting a vertically disposed surface parallel to and spaced one-half of the length of said modulus from the central plane of said section to position the end of another section on a modular line in the structure.

3. A building section adapted to be assembled with other sections to form the vertical walls of a structure, said section having a vertically and longitudinally disposed central plane, and having horizontal dimensions which are a whole multiple of a modulus that is a whole number of inches in length, said section embodying a sub-assembly located in said section in position to be engaged by the end of another section and comprising a conventional wooden timber having its longest dimension extending vertically in said section and having horizontal dimensions which are not a whole number of inches in length, said timber being centered with respect to the central plane of the section, and means secured to said timber presenting a vertically disposed surface parallel to and spaced one-half the length of said modulus from said central plane to position the end of another section on a modular line in the structure.

4. A building section adapted to be assembled with other sections to form the vertical walls of a structure, said section having a vertically and longitudinally disposed central plane, and having horizontal dimensions which are a whole multiple of a modulus that is a whole number of inches in length, said section embodying a sub-assembly located in said section in position to be engaged by the end of another section comprising a conventional wooden timber having its longest dimension extending vertically in the section and having horizontal dimensions which are not a whole number of inches in length, said timber being centered with respect to the central plane of the section, and means secured to said timber and presenting oppositely facing, vertically extending surfaces which are parallel to and each spaced one-half the length of said modulus from said central plane on opposite sides

thereof to position the ends of other sections on modular lines and the length of said modulus apart in said structure.

5. A building section adapted to be assembled with other sections to form the vertical walls of a structure, said section having a vertically and longitudinally disposed central plane, and having horizontal dimensions which are a whole multiple of a modulus that is a whole number of inches in length, said section embodying a sub-assembly located in said section in position to be engaged by the end of another section and comprising two conventional wooden timbers having their longest dimensions extending vertically in the section and having horizontal dimensions which are not a whole number of inches in length, said timbers being centered with respect to the central plane of said section, and a third timber located between said first two timbers and secured thereto in horizontally displaced relation, said third timber presenting a vertically disposed surface parallel to and spaced one-half the length of said modulus from the central plane of said section to position the end of another section on a modular line in the structure.

6. A building section adapted to be assembled with other sections to form the vertical walls of a structure, said section having a vertically and longitudinally disposed central plane, and having horizontal dimensions which are a whole multiple of a modulus that is a whole number of inches in length, said section embodying a sub-assembly located in said section in position to be engaged by the end of another section and comprising two conventional wooden timbers having their longest dimensions extending vertically in the section and having horizontal dimensions which are not a whole number of inches in length, said timbers both being centered with respect to the central plane of said section, and two other timbers located between the first two and secured thereto in horizontally displaced relation, said other two timbers presenting oppositely facing, vertically extending surfaces which are parallel to and each spaced one-half the length of said modulus from said central plane on opposite sides thereof to position the ends of other sections on modular lines and the length of said modulus apart in said structure.

7. A building section adapted to be assembled with other sections to form the vertical walls of a structure, said section having a vertically and longitudinally disposed central plane, and having horizontal dimensions which are a whole multiple of a modulus that is a whole number of inches in length, said section embodying a sub-assembly located in said section in position to be engaged by the end of another section and comprising a conventional wooden timber which has its longest dimension extending vertically in the section and horizontal dimensions the length of which is less than said modulus, said timber being centered with respect to the central plane of said section, and means secured to said timber and projecting horizontally therefrom presenting a vertically extending surface parallel to and spaced one-half the length of said modulus from the central plane of said section to position the end of another section on a modular line in said structure.

8. A rectangular building section adapted to be assembled with other building sections to form the vertical walls of a structure, said section having a horizontally extending top plate, a horizontally extending bottom plate and a plurality of

vertically extending studs connected to said top plate and said bottom plate, said section having horizontal dimensions which are equal to a whole multiple of a modulus that is a whole number of inches in length and having a central plane which passes through said top plate, said bottom plate and said studs, said studs being formed of conventional wooden timbers having horizontal dimensions which are not a whole number of inches in length and being centered with respect to the central plane of the section, and a sub-assembly embodied in said section and positioned to be engaged by the end of another section, said sub-assembly comprising a conventional wooden timber similar to said studs and extending vertically from said bottom plate to said top plate and centered with respect to said central plane and means secured to said timber and presenting a vertically extending surface parallel to and spaced one-half of the length of said modulus from said central plane to position the end of another section on a modular line in said structure.

9. A building section of the character set forth in claim 3 having wall board applied thereto parallel to the central plane of the section and

5 having the edge thereof bearing against the centered conventional wooden timbers of the sub-assembly and lying adjacent the vertically disposed surface of said means whereby said surface is exposed to position another section on a modular line in said structure.

10. A building section of the character set forth in claim 7 having wall board applied thereto parallel to the central plane of the section and having the edge thereof bearing against the centered conventional wooden timber of the sub-assembly and lying adjacent the vertically disposed surface of said means whereby said surface is exposed to position another section on a modular line in said structure.

11. A building section of the character set forth in claim 8 having wall board applied to said section parallel to said central plane and in engagement with said studs, the edge of said wall board bearing against the centered timber of said sub-assembly and lying adjacent the vertically extending surface of said means, whereby said surface is exposed to position the end of another section on a modular line in the structure.

FRANCIS VAUX WILSON, JR.
JOHN W. GERMOND.
